UNITED STATES PATENT OFFICE.

IRVING J. CROMER, OF KANSAS CITY, MISSOURI.

SWIMMING APPARATUS.

Application filed September 16, 1925. Serial No. 56,634.

To all whom it may concern:

Be it known that I, IRVING J. CROMER, a citizen of the United States, and a resident of Kansas City, in the county of Jackson 5 and State of Missouri, have invented a certain new and useful Improvement in Swimming Apparatus, of which the following is a specification.

My invention relates to improvements in 10 swimming apparatus. It relates to an apparatus which has sufficient buoyancy to support a person, and which has means for being propelled by the person.

One of the objects of my invention is to 15 provide a novel swimming apparatus of the kind described, which is simple, cheap, durable, not liable to get out of order, which is adapted for use by persons of different height, which is safe, and which will afford 20 exercise and enjoyment to the user while enabling him to learn the art of swimming.

The novel features of my invention are hereinafter fully described and claimed.

In the accompanying drawing, which 25 illustrates the preferred embodiment of my invention,

Fig. 1 is a perspective view of my improved swimming apparatus.

Fig. 2 is a side elevation of the same.

Fig. 3 is an enlarged sectional view on the line 3—3 of Fig. 2.

Similar reference characters designate similar parts in the different views.

A buoyant support is provided, which may 35 comprise a frame consisting of two spaced apart floats, which may be two boards 1, to which are fastened at the inner edges thereof respectively two rearwardly extending wooden bars 2, to the inner sides of each 40 of which are fastened two depending vertical bars 3. Two longitudinal brace bars 4 are respectively fastened to the under edges and rear ends of the bars 2, and to the inner sides of the adjacent depending bars 3.

45 A body support comprising a horizontal transverse board 5 has its ends respectively fastened to the inner sides of the brace bars 4 in substantial alinement with the transverse middle portions of the floats 1.

50 A transverse handhold bar 6 may be fastened at its ends to the forward ends respectively of the floats 1.

Propelling means for the apparatus may 55 consist of two propelling wheels, which are, preferably, paddle wheels 7, which are respectively fastened to and rotatable with two

transverse aligned shafts 8. Two pairs of bearings 9 are respectively mounted on the upper sides of the floats 1 and have respectively rotatably mounted in them the 60 shafts 8.

For rotating the shafts 8, there are respectively secured to them two bevel gear wheels 10 which respectively mesh with two bevel gear wheels 11, which are respectively 65 rigidly secured to two longitudinal shafts 12, which are rotatably mounted adjacent to their forward ends in transverse plates 13, which are respectively fastened between the pairs of bearings 9. The rear portions of 70 the shafts 12 are respectively rotatable and longitudinally slidable in two lugs 14 respectively provided on the outer sides of two bearing members 15, which are respectively forwardly and rearwardly adjustably fastened to the rear portions of the bars 2 by 75 bolts 16 which extend through slots provided longitudinally, one in each bar 2 and designated by 17.

A crank shaft 18 extends transversely 80 through the slots 17 and is rotatably mounted in the bearing members 15. The crank shaft 18 has two oppositely disposed cranks 19, which are adapted to be respectively engaged and turned by the feet of the person 85 operating the apparatus. Respectively rotatable on the cranks 19 are stirrups 20 through which the operator inserts his feet.

Secured rigidly on the ends of the crank 90 shaft 18 are two bevel gear wheels 21, which respectively mesh with two bevel gear wheels 22, which are respectively splined to the shafts 12 so as to slide thereon and rotate therewith.

The bolts 16 are loosened and the bearing 95 members 15 are then adjusted on the bars 2 to position the crankshaft 18 to suit the height of the person who is to operate the apparatus. The bolts 16 are then tightened.

In the operation of the apparatus, the person disposes himself face down with his breast upon the board 5, his hands grasping the handhold 6, and his feet in the stirrups 20, as shown in dotted lines in Fig. 2.

If the operator now with his feet rotates 100 the crank shaft 18 in a clock-wise direction, as viewed in Fig. 2, the paddle wheels 7 will be rotated in a like direction by means of the gear wheels 21 and 22, shafts 12, gear wheels 11 and 10 and shafts 8, thereby propelling the apparatus, and with it the person, in a forward direction. The operator 110

by reversing the direction of rotation of the crank shaft can propel the apparatus backwardly.

The distribution of the weight of the person and the buoyant material is such that during the operation of the apparatus, and when the person is resting, the floats will remain substantially horizontal.

I do not limit my invention to the structure shown and described, as modifications, within the scope of the appended claims, may be made without departing from the spirit of my invention.

What I claim is:—

- 15 1. In a swimming apparatus, a buoyant frame comprising two spaced apart floats, a body support between and connecting said floats, and two rearwardly extending bars, two propelling wheels rotatably mounted on said floats respectively, two bearing members respectively forwardly and rearwardly adjustable on said bars, a crank shaft rotatably mounted in said bearing members and having two oppositely disposed cranks adapted to be respectively engaged and turned by the feet of a person lying on said body support, and means actuated by said shaft for rotating said propelling wheels.
- 30 2. In a swimming apparatus, a buoyant support adapted to support the body of a person, two propelling wheels rotatably mounted on said support, two bearing members forwardly and rearwardly adjustable on said support, a transverse shaft rotatably mounted on said bearing members and having two oppositely disposed cranks adapted to be respectively engaged and turned by the feet of the person, two bevel gears secured to and rotatable with said shaft, two longitudinal rotary shafts mounted respectively in said bearing members and longitudinally slidably therein, two bevel gears respectively secured to said longitudinal shafts and adjustable longitudinally thereon and respectively meshing with the first named gears, and means actuated by said longitudinal shafts for respectively rotating said propelling wheels.
- 45 3. In a swimming apparatus, two floats, a body supporting member intermediate of and supported by said floats, two rearwardly extending bars secured to said floats, two bearing members respectively forwardly and rearwardly adjustable on said bars, a transverse shaft rotatable in said bearing members and having two oppositely disposed cranks adapted to be engaged and turned by the feet of a person lying on said body supporting member, two propelling wheels respectively carried by said floats, and means actuated by said shaft for rotating said propelling wheels.
- 60 4. In a swimming apparatus, two floats, a

body supporting member between and supported by said floats, two rearwardly extending bars carried by said floats respectively, two bearing members respectively forwardly and rearwardly adjustable on said bars behind said body supporting member, a transverse shaft rotatably mounted in said bearing members and having two oppositely disposed cranks adapted to be respectively engaged and turned by the feet of a person on said body supporting member, two propeller wheels having respectively two transverse shafts respectively rotatably mounted on said floats, and driving means connecting said last named shafts with said crank shaft.

5. In a swimming apparatus, two floats, a body supporting member between and supported by said floats, two rearwardly extending bars respectively carried by said floats, two bearing members respectively forwardly and rearwardly adjustable on said bars, a transverse crank shaft rotatable in said bearing members and having two oppositely disposed cranks adapted to be engaged and turned by the feet of a person on said body supporting member, two propelling wheels having respectively two transverse shafts rotatably mounted on said floats respectively, two longitudinal shafts rotatably mounted respectively in said bearing members, and driving gearing connecting said longitudinal shafts with said propelling wheel shafts and with said crank shaft.

6. In a swimming apparatus, two floats, a body supporting member between and supported by said floats, two rearwardly extending bars carried by said floats respectively, two bearing members respectively forwardly and rearwardly adjustable on said bars, a transverse crank shaft rotatable in said bearing members and having two oppositely disposed cranks adapted to be engaged and turned by the feet of a person on said supporting member, two propelling wheels having respectively two transverse shafts respectively rotatable on said floats, two longitudinal shafts rotatable respectively in said bearing members and slidably therein, two gears secured to said crank shaft, two gears respectively secured to said propeller wheel shafts, two gears respectively secured to said longitudinal shafts and respectively meshing with the last named gears, and two gears respectively meshing with the gears on said crank shaft and rotatable with and longitudinally adjustable respectively on said longitudinal shafts.

In testimony whereof I have signed my name to this specification.

IRVING J. CROMER,
